UNITED STATES PATENT OFFICE.

MATTHEW A. BATSON, OF SPRINGFIELD, MASSACHUSETTS.

FLYING-MACHINE.

1,077,786.

Specification of Letters Patent.

Patented Nov. 4, 1913.

Application filed June 22, 1911. Serial No. 634,667.

To all whom it may concern:

Be it known that I, MATTHEW A. BATSON, a citizen of the United States of America, residing at Springfield, in the county of 5 Hampden and State of Massachusetts, have invented new and useful Improvements in Flying-Machines, of which the following is a specification.

The present invention relates to improvements in flying machines or aeroplanes in which two or more wing elements are employed, the wing elements serving to practically support the machine in flight while it is driven forward by means of one or 15 more propellers rotating in a vertical plane transverse to the line of motion.

The objects of the invention are: (1) to provide a flying machine in which the different elements will tend to keep it in stable 20 equilibrium, both laterally and longitudinally, while in flight, in practically every condition of the atmosphere in regard to varying atmospheric pressures or densities which produce gusts of wind, billows, or 25 eddies; (2) to provide means for keeping the machine in a forward, gliding motion, should the motors for any reason come to a standstill or be stopped, and thus prevent its upsetting or falling vertically; (3) to 30 provide means for steering, both vertically and horizontally; (4) to provide a flying machine in which two or more motors may be installed, each independently operative and of sufficient power, to drive the machine 35 safety in flight; (5) to provide means for simultaneously adjusting the wing elements in a vertical plane, parallel with the longitudinal axis of the machine, also to permit independent movements of these elements in 40 a vertical plane transverse to the longitudinal axis of the machine; (6) to provide means to guide or direct the course of the machine so as to steer it either to the right or the left, and also in the provision 45 of means for causing the machine to ascend or descend by varying the angle of incidence of the wing; (7) to provide means for permitting the machine to alight upon, or start from, either land or water; (8) to provide 50 means for causing the machine to rise without being first put in a forward horizontal motion; (9) to provide a tail element for causing the machine to right itself and assume a gliding action, should the propelling 55 mechanism, for any reason, become disabled.

In order to effect the lateral equilibrium,

of the machine, I have attached a plurality of laterally disposed wing elements to the framework of the machine with spring or elastic elements which will permit them to 60 yield or move so as to accommodate themselves to the different densities of the atmosphere, and have also so constructed these wing elements as to direct the current of air from their outer ends or tips toward the 65 central portion of the machine.

Having set forth the principal objects and nature of the invention, I will now more particularly describe my flying machine in which these principles are embodied in a 70 practical form, it being understood that variations from this ideal construction may be made without altering or invalidating the claims, as more particularly set forth later on.

In the drawings forming part of my application,—Figure 1 is a plan view of the machine showing the arrangement of the wing elements in different vertical planes, the forward elevating or horizontal rudder, 75 the tail, and, in outline, the car body. Fig. 2 is a side elevation showing the arrangement of the driving propellers, the wing elements, fore and aft rudders, front elevator, tail, also the pontoons on which are 80 pivotally mounted wheels for permitting the machine to readily get under headway in starting from a state of rest. Fig. 3 is a detailed view showing the manner of mounting the wing elements so as to vary 85 the angle of incidence. Fig. 4 is a front elevation showing the arrangement of the wing elements in the different horizontal planes, and the elastic elements extending “billows” or “holes,” in the air similar to 90 permit the latter to automatically yield in an upward direction, and in dotted lines the second position assumed by the wings. Fig. 95 5 is a view showing the arrangement of the hand wheels in the pilot room for varying 100 the angle of incidence of the wings, and also means for varying the position of the horizontal and vertical rudders. Fig. 6 is a detailed view of the tail-piece and its wing elements. Fig. 7 is a detailed view of the 105 spring element which is connected between the frame and the wing, this element being so constructed as to permit the wing to move upward and downward, but not below a horizontal plane. Fig. 8 is a plan view 110 showing, in detail, the construction of the wing and the means of attaching the same

to the framework for permitting the angle of incidence to be varied. Fig. 9 is a transverse sectional view on the line 9-9, Fig. 8, showing the curvature of the wing. Fig. 5 10 is a sectional view on the line 10-10, Fig. 5, showing the means for operating the pilot-wheels for varying the position of the wing elements and the various rudders. Fig. 11 is a side elevation showing the construction of the wing and means of varying its angle of incidence. Fig. 12 is a diagrammatic view illustrating the position and action of the tail element to right the ship, should the propelling means become stalled. Fig. 13 is a detail of the swivel connection of the pontoons and trucks with the chassis. The chassis of the machine consists of the beam elements *d* and the spine *i* placed horizontally and practically parallel and framed and trussed together by posts and struts *b*, *c*, (shown in Fig. 4) so that a transverse section of the chassis will present practically an equilateral triangle with the spine at the apex of the angle formed by the inclined 25 side post elements and the beams at the other angles of the triangle. Midway of the base of the triangle, and parallel with the beams, is suspended the car which incloses the engines, pilot room, capacity for passengers, supplies, etc. The chassis is mounted on pontoons *g* for supporting the machine on water and to enable it to start therefrom. Mounted on the pontoons are trucks *e* having wheels *f* thereon which, as shown in Fig. 2, are adapted to be folded upward into the dotted line position shown at the left of this figure, and are for the purpose of permitting the machine to readily get under headway when starting from the ground. 40 The wheels are folded upward when in flight, being used only for getting under headway on land. The pontoons are provided with skids to prevent injury when lighting on land.

45 The upper ends of the post elements *b* and *c* are connected to the longitudinal spine element *i*, and the lower ends to the longitudinal beams *d*.

j designates a series of laterally disposed wings attached to the upper part of the chassis and arranged in substantially the same horizontal plane.

k designates the second series of laterally disposed wings attached to the lower part of the chassis (or, as shown, to the car) and arranged in the same horizontal plane with relation to each other.

It will be noticed, by referring to Figs. 1 and 2, that these series of wings *j* and *k* are not placed exactly under each other but are arranged so that given points (as the front edge) of the upper and lower series of wings will be in alternate, practically equidistant, vertical planes transverse with the axis of the chassis. If these vertical

planes are numbered consecutively from front to rear, the odd numbered ones (1, 3, 5, 7) will cut the front edges of the wings of the upper series *j*, and the even numbered ones (2, 4, 6, and 8) will cut the front edges of the wings of the lower series *k*. Attached to the under side of these wings is a spring element *p* which comprises a rod *q* that is attached to the under side of the wings at *r*. The end of the rod *q* is provided with a plunger *s* which is located between a compression spring *t* and a plug or stop *s'* through which the rod *q* passes. The plunger *s* works in a barrel element *u*, the lower end of which is provided with small openings or vents *v* whereby when the plunger *s* rapidly descends as the wings move downward it will force the confined air through these small openings *v* thereby producing a cushioning effect on the wings when they descend to a horizontal position. The lower end of the spring element *p* is attached to the chassis at *w*.

The object of pivoting the wing *j* and *k* to the chassis so that they may rise and fall, as indicated at Fig. 4, is for the purpose of assisting in maintaining the machine in a stable equilibrium when the wings come into contact with different densities or atmospheric pressures, sometimes spoken of as "billows" or "holes" in the air similar to the wave crests and hollows on the surface of the water. These wing elements can, therefore, readily accommodate themselves to the position shown in dotted lines at *j'* and *k'* in Fig. 4, depending upon the different air densities encountered.

Referring now to the mechanism by means of which the angle of incidence of the wings is changed, reference being had to Figs. 2, 3, 8, and 9 in which the chassis part of the frame may be indicated at *x*: Pivotedly attached to this part of the chassis is a sector element *y*, the pivotal point of the sector being designated at *z*. The inner side of the wing is provided with a rod *3* which is attached to the sector element *y* by means of the eye elements or pivots designated at 4, which eye elements permit the wings *j* and *k* to rise and fall in a vertical plane transverse to the axis of the chassis, as previously described. At the same time the wing may be rocked fore and aft of the chassis so as to change its angle of incidence by means of the sector element *y* which is provided with teeth 7; and engaging these teeth is a worm 8 on the end of the shaft 9. It will therefore be seen that by revolving the shaft 9 the engagement of the worm 8 with the teeth 7 will cause the sector to turn with the longitudinal axis of the machine and rock the entire wing so as to vary the angle of incidence of the edge 5 whereby more or less of the air may be directed above 130

or below the wing during flight. At the same time the wing is free to rise and fall on the pivots 4 in a vertical plane transverse to the length of the ship. To permit the angle of incidence of the wings of either side in each series to be changed simultaneously, the lower ends of the shafts 9 are provided with pulleys or drums 10 over which cables or ropes are passed so that all the pulleys may be moved simultaneously. The wing is provided with a balancing portion which extends transversely to the line of flight and a base portion which extends longitudinally, or parallel to, the line of flight, the transverse cross-sections of both portions being concave below to form channels, the channel in the transverse part inclining forwardly and laterally of the machine and merging into the channel in the longitudinal portion and at an obtuse angle thereto. The drums or pulleys 10 of the series of wings *j* and the pulleys 15 of the series of wings *k* are joined together by cables or wire ropes 11 and 15². The connection to the upper cable 11 is shown in the middle of Fig. 2, and passes downward, as shown at 12, over the pulley 13 and under the pulley 15¹ where it is connected to one of the pulleys 15 thus joining all the pulleys on one side of the machine together. Attached to the pulleys 15 are cables 33 which lead to the pilot house 16 so that when the two cables 11 and 15² are operated all the wings on one side of the ship may be rocked simultaneously on the pivots 2. The cables 33 on both sides of the ship pass over pulleys 15³ (as shown in Fig. 5) and from these pulleys the cables 33 lead to drums 31 and 32.

In order to operate the wings from the pilot room, shown in Fig. 5 and designated by 16, pilot wheels 17 and 18 are employed which are mounted on two hollow shafts 19 and 20, as shown in Fig. 10.

21 and 22 indicate pulleys that are mounted on the shafts 19 and 20 and are connected by a straight belt 23. The pulley 22 is rigidly fixed to its shaft, while the pulley 21 is loose on its shaft, but provided with a perforated plate 27, to receive a pin 28, which is adapted to enter an opening 30 in the wheel 17 for fixing or clamping the pulley 21 to its shaft; also mounted on the hollow shafts 19 and 20 are pulleys 24 and 25 which are connected by a cross-belt 26, the pulley 24 being fixed on its shaft, and the pulley 25 loose on its shaft but provided with a perforated plate and pin 29 for fixing or clamping it so that it shall revolve with its shaft. Any other suitable means may be employed to temporarily secure the pulleys 21 and 25 to the shafts, than that described.

Rigidly mounted on the hollow shafts 19 and 20 are winding drums 31 and 32 with 65 which the cables 33 are connected that lead

to the cables which connect the drums or pulleys 10 and 15. When it is desired to change the angle of incidence of all the wings on one side of the ship, independently of those on the other side, the pilot wheel 17 or 18, corresponding to that side of the machine, will be rocked in the required direction, that is upward or downward, leaving both pulleys 21 and 24 loose upon their shafts. 70

Should it be desired to simultaneously increase or decrease the angle of incidence of these wings on both sides of the ship, the pulley 25 is fixed or clamped on its shaft and either pilot wheel 17 or 18 rotated in the required direction. Should it be desired to increase the angle of incidence of all the wings on one side of the ship, and simultaneously decrease the angle of incidence of all the wings on the other side of the ship, the pulley 21 will be made rigid upon its shaft and either pilot wheel rotated in the required direction. Suitable means are also provided in the pilot room of the car for operating both the horizontal and vertical 85 rudders at the fore and aft part of the machine. 90

The horizontal rudder 42 is operated by cables 40 and 41 which lead back to the wheel 60 in the pilot room. The front vertical rudder 58 is operated from the drum 38 and hand-wheel 36, shown in Fig. 10. The rear vertical rudder 59 is operated by the drum 39 and hand-wheel 37, shown in Fig. 10. The tail 49 is operated by the wheel 61 100 in the pilot-room which is connected thereto by means of the cables 47 shown in Fig. 2, and by means of which it may be raised and lowered.

Three motor or power plants 53 are provided, each motor being independently operative and of sufficient power to drive the machine in its flight, should the other motors be stopped. Suitable propellers are connected with the motors either by direct connection or by belts, or other transmission. The tail-piece 49 is pivotally attached to the rear end of the spine *i* at 46 and is free to rock or oscillate through a limited arc on its pivot, where it is connected to the spine. The tail-piece comprises the curved wing portions 50, the main, outward flaring plane portion 49 which is rigidly connected to the curved wing portions 50, and the flexible parts 48 which are secured to the main plane portion 49. The curved wing-portions 50 of the tail are formed with a concave under surface similar to the balancing portions of the wings which lie transversely to the line of flight, as shown in Fig. 9, which 115 is a section on the line 9—9 of Fig. 8. 120

When the ship is not in motion, the tail falls or descends to an angular position of about 6 degrees below the horizontal giving the wings 50 approximately the normal 130

angle of incidence for aeroplanes prepared to start in flight, as shown in Fig. 2 in dotted lines at 57¹. In flight, this angle automatically becomes less as the speed increases, due to the pressure of the air currents under the plane portion of the tail. (The portions 48 and 49 of the tail-piece are made of flexible material and thus yield to the various atmospheric densities of the air during flight.)

Should the forward momentum of the ship suddenly cease for any cause, and the ship begin to fall, the upward pressure of the air, on the under side of the tail, causes it to assume an inclined position, as shown by dotted lines 57 in Fig. 2. At the same time the angle of incidence of the curved wing portion 50 of the tail is decreased. It can readily be seen that this position of the tail will cause the ship to take a forward, gliding direction, the horizontal component becoming greater as the speed increases, due to the lifting power of the main aeroplanes or wings. This automatic righting action of the tail-piece is its main purpose. However, flexible portions 48 are provided which may be operated in the same or opposite directions to cant the tail for the purpose of assisting in maintaining equilibrium and in turning. The tail-piece itself may also be mechanically raised or depressed by means of cables 50¹ for the purpose of pointing the ship upward or downward, or for maintaining it on an even keel, in flight.

The wing elements consist of two parts, (1) the part adjacent the chassis (hereinafter called the base portion) being constructed somewhat similar to the sector of a hollow cylinder extending in a fore and aft direction, and is inclined slightly downward to the rear, as shown in Fig. 2, the concave side being underneath; and (2d) the portion extending horizontally outward and slightly forward from the base portion and curved underneath comprising the wing proper, and hereinafter called the wing. This construction of the wing element tends to guide or deflect the displaced air inward toward the chassis, as indicated by the arrows at 55, where it is condensed or banked under the base portions of the wing elements. The arrangement of the wing elements is such that the rear end of the base portions is nearly under the forward ends of the following wings, the air currents escaping from the base portion as the forward wing rises underneath its following wing and thus continues to assist in sustaining the weight. The construction of the wing elements also affords a means for causing the machine to rise, due to the backward drafts forced under them from the propellers 52.

On account of the propellers drawing the

air inward and forcing it rearward it becomes necessary to provide the base portion *m* of the wings 1, 3, and 7 with valves 62 which permit air to pass downward through the wing, but not upward, in order to prevent a downward pressure upon the upper side of the base portion *m* caused by the rotating propellers. These openings therefore relieve the wings of this downward pressure by allowing the air to reach the propellers through these openings.

Referring more particularly to the automatic righting operation of the tail element of my machine, reference is had to Fig. 12 in which the spine *i* of the chassis is conventionally represented by a single line: First, let it be assumed that the machine is moving forwardly at a uniform rate of motion, the position of the plane part 49 of the tail is that shown in full lines which is substantially in line with the chassis, and the chord of the curved part of the wing 50 is also in line with the part 49. Now considering the propelling means as having come to a standstill or been disabled and the machine to have fallen on an even keel into the dotted line position *i*¹: The tail 49 has been forced upward into the dotted position 49¹ by the pressure of air below, as indicated by the arrows 49². The effect of the supporting wings *j* and *k*, and the wing 50 against the action of gravity causes the machine to assume a gliding direction, as indicated by the arrows 49³. The machine would therefore reach the earth by a succession of glides or falls. The operator may, of course, adjust the wings *j* and *k* so as to bank the air under the same to offset a greater support on the machine and prevent its falling abruptly, but will reach the earth by a succession of glides and falls.

A lifting and starting gear is shown in Figs. 1 and 2 and consists of the pontoons *g*, the trucks *e*, and wheels *f*. The pontoons consist of water-tight boxes attached to the chassis *a* by the spring elements *e*¹ and the swivels *e*² and are used principally for alighting upon, starting from, or moving upon the surface of the water. The spring elements and the swivels are connected to the pontoons by a universal or ball and socket connection *e*³. The spring elements *e*¹ consist of two straight rods *e*⁴ and *e*⁵ rigidly connected together at the bottom, one of the rods of said connection having a right angle therein, and the other an obtuse angle, as shown at *e*⁶ and *e*⁷. The upper ends of the rods *e*⁴ and *e*⁵ pass through the barrels *e*⁸ (see Fig. 14) which are joined to the chassis by swivels *e*⁹ to permit the rods to swing in a fore and aft direction. The springs *e*¹ act as cushions for the pontoons when alighting, and when running over the uneven ground.

The bevel side of the yoke formed by the rods e^4 and e^5 is placed outwardly to permit the pontoon to rest evenly upon the ground or water when the ship is tilted to one side, as shown in the dotted position in Fig. 4, or when the land or water surface is uneven. The truck e consists of the axle e^{19} having bearings e^{10} resting upon the central outer edges of the pontoons, the axles extending beyond the outer edges of the pontoons and being provided at either end with swiveled forks e^{11} for the wheels. Provision is made for folding the wheels upward, when not in use. The wheels are used primarily for starting the ship and for moving it easily about when on land. The pontoon is also provided with runners or skids e^{12} and primarily for alighting on the ground and to prevent the wheels from dropping into ruts or holes and being damaged. The car or cabin of the machine is shown at 65 and extends fore and aft and is hung from, or supported by, the trussed chassis a .

In order to move the parts 48 of the tail, I provide cables or cords 49¹, 49², 49³, and 49⁴ which I extend to the pilot room of the cabin around a suitable common drum for canting the tail so as to change the course of the machine. In practice, these cords will be so arranged that one pair, as 49¹ and 49⁴, will cant the tail by pulling up on one cord and down on the other; the other pair of cords 49² and 49³ being of course in a slack condition. When the tail is canted in the opposite direction the cords 49² and 49³ will be taut and 49¹ and 49⁴ slack. Suitable pulleys would, of course, be necessary to maintain the cords 49¹ and 49² above the horizontal plane of the tail and 49³ and 49⁴ below the horizontal plane in order to effect the desired canting of the tail.

The front and rear vertical rudders 58 and 59 are provided to assist in turning the machine and to enable the ship to tack against the wind in practically the same manner as a sailing vessel tacks against the wind. For example, should it be desired to cross a strong wind at practically right angles, the machine is headed slightly into the wind and both rudders are then held so that the wind will strike them on the lee side of the ship,—one or both being shifted to keep the ship headed properly. The side-wise operation of the rudder 13 is accomplished by pulling down on one of the cords 49¹ and upward on the other, the result being that the whole effect is to cant the rudder sidewise. It should be noticed from the construction herein shown and described that the air which is banked or compressed under a forward wing when it escapes in this compressed condition will immediately pass under the succeeding or following wing and exert its elastic or expansive force on

this second wing and thus materially assist in supporting the ship. The same operation being, of course, repeated from wing to wing.

In the operation of the machine, the angles of incidence of the wings will, of course, be set or adjusted when the machine is assembled so as to obtain the best results—that is to say, the greatest supporting effect. This adjustment of the wing during the assembling operation is effected, as clearly shown in Figs. 9 and 11, by rotating the individual shafts 9, the teeth 8 of which mesh with the teeth 7 of the sector elements y whereby the angle of incidence or the position of any individual wing may be set before the cables 11 and 15² are permanently attached to the pulleys 10 and 15; then, when these cables are operated from the pilot-house all of the pairs of wings will be simultaneously operated. The angles of incidence of the wings 85 may be such that one wing may be positive and the adjacent wing negative. Such a position is shown in Fig. 2 wherein the angle of incidence of the wing 50, indicated in dotted lines, is negative, and the angle of incidence of the next preceding wing is positive.

What I claim, is:—

1. In a flying machine, the combination with a chassis structure, wings pivotally attached thereto, means to permit the wings to yield independently of each other and without control by the aviator to the increasing air forces, and to return with the decreasing air forces to their normally horizontal position, said movement being in a vertical plane transverse of the line of flight, means of varying the angle of incidence of the wings, and means to propel the machine.

2. In a flying machine, the combination with a chassis structure, wings attached thereto, means to permit the wings to automatically move upwardly independently of each other from a horizontal position, means to vary the angle of incidence of the wings, and means to propel the machine.

3. In a flying machine, the combination with a chassis structure, wings pivotally attached thereto, means to permit the wings to yield independently of each other and without control by the aviator to the increasing air forces and without varying the angle of incidence, and to return with the decreasing air forces to their normally horizontal position, said movement being in a vertical plane transverse of the line of flight, and means to propel the machine.

4. In a wing for flying machines substantially L-shaped consisting of a balancing portion transverse to the line of flight, and a base portion longitudinal to the line of flight, each portion being curved in cross section and concaved underneath to form

channels, the channel of the transverse portion merging into that of the base portion, the base portion of the wing being adjacent to the point of attachment to the chassis, substantially as described.

5. A wing for a flying machine having a balancing portion extending transversely to the line of flight, and a base portion extending longitudinally of the line of flight, the transverse cross-sections being concave from below to form channels, the channel in the transverse part merging into the channel in the longitudinal part at an obtuse angle thereto, whereby the waves of air during flight will be guided or directed from the transverse portion toward and under the longitudinal portion.

6. A tail-piece for flying machines comprising a plane portion and curved wing portions to collect the air during flight, and flexible members attached to the plane portion of the tail, and means for operating the flexible members.

7. In a flying machine, the combination with the chassis, vertical rudder, and means for propelling the machine, of wings having a balancing portion extending transversely to the line of flight, and a base portion extending longitudinally of the line of flight, the transverse cross sections of both portions being concave below to form channels, the channels in the transverse part inclining forwardly and laterally of the machine and merging into the channel in the longitudinal part, at an angle thereto.

8. In a flying machine, the combination with a chassis, means to propel the same, of a tail for steering, wings pivotally attached to the chassis, elements permitting the same to rise and fall independently of each other, said movement of the wings being due entirely to varying densities of air, gusts, or eddies, and means for varying the angle of incidence of the wings.

45 9. In a flying machine, a chassis, a car or cabin attached to the chassis, wing elements attached to the chassis, means between the wing elements and the chassis to permit the wing elements to move upward independently of each other from their initial or horizontal position and to return to this position without varying the angle of incidence, said movement being automatically caused by the varying densities of the air and the forces of air currents which act upon said elements.

10. In a multiplane flying machine comprising a chassis, a car or cabin attached to said chassis, two or more pairs of wing elements pivotally attached to the chassis, means to simultaneously vary the angle of incidence of all the wing elements, means to permit the wings to automatically yield independently of each other and without control of the aviator to the varying air

forces and to return with the decreasing air forces to their normal horizontal position, said movements being in a vertical plane transverse to the line of flight, and means to propel the machine.

70 11. In a flying machine, the combination with a chassis structure, a car longitudinally suspended therefrom, wings attached thereto, means to permit the wings to yield upwardly from a horizontal position, means to vary the angle of incidence of the wings, and means to propel the machine.

75 12. In a flying machine, the combination with a chassis structure, a car longitudinally suspended therefrom, wings attached thereto, means to permit the wings to yield upwardly from a horizontal position, means to vary the angle of incidence of the wings, means to propel the machine, and means to steer the machine horizontally.

80 13. A multiplane flying machine comprising a chassis or frame, wings pivotally attached thereto in two horizontal planes, means to permit the wings to yield independently of each other to the varying forces of the air in a plane transverse to the line of flight, means for simultaneously varying the angle of incidence in the same or opposite directions on both sides of the ship, and means to propel the machine.

85 14. A multiplane flying machine comprising a chassis or frame, wings pivotally attached thereto in two horizontal planes, means to permit the wings to yield independently of each other to the varying force 90 of the air in a plane transverse to the line of flight, means to vary the angle of incidence of the wings on one side of the ship independently of those on the other side of the ship.

95 15. A wing for a flying machine which is substantially L-shaped and consisting of a balancing portion transverse to the line of flight, and a base portion longitudinally arranged to the line of flight; each portion being curved in cross section and concave underneath to form channels, the channel of the balancing portion merging into that of the base portion.

100 16. A wing for a flying machine comprising a balancing portion extending laterally and forwardly to the line of flight, and a base portion extending longitudinally of the line of flight, the transverse cross sections of both portions being from below to form channels, the channel in the balancing part merging into the channel of the longitudinal part at an obtuse angle thereto.

115 17. In a flying machine, the combination with the framework thereof, of vertical rudders, means to propel the machine, wing elements, each wing element consisting of portions,—first, the portion adjacent to the framework comprising a sector of a hollow cylinder and extending in a fore and aft di- 120 125 130

rection, the concave side being underneath, and, second, the portion extending from the base portion transversely of the line of flight and slightly forward so as to form an 5 obtuse angle with the base portion and curved underneath to form a channel, said channel merging into that of the base portion.

18. In a flying machine, the combination 10 of the framework, means to propel the same, wings pivotally attached to the framework, elastic elements connecting a central portion of each wing to the framework to permit the wings to rise and fall independently of each 15 other in varying densities of air, gusts, or eddies, and means for varying the angle of incidence of the wings.

19. In a flying machine, the combination 20 with a chassis structure, wings attached thereto, means to permit the wings to automatically move upwardly independently of each other from a horizontal position, means

to vary the angle of incidence of the wings, means to propel the machine, a tail, and means to cant or bend the rear portion of 25 the tail.

20. In a flying machine, the combination with the chassis, vertical rudder, and means for propelling the machine, a horizontal rudder for steering upward and downward, 30 of wings having a balancing portion extending transversely to the line of flight, and a base portion extending longitudinally of the line of flight, the transverse cross sections of both portions being concave below to form 35 channels, the channels in the transverse part inclining forwardly and laterally of the machine and merging into the channel in the longitudinal part, at an angle thereto.

MATTHEW A. BATSON.
